UNITED STATES PATENT OFFICE.

JOHN Z. TOW, OF SPRINGFIELD, TENNESSEE, ASSIGNOR OF ONE-THIRD TO MORDAUNT PATTERSON AND ONE-THIRD TO SAMUEL R. MURPHEY, BOTH OF SPRINGFIELD, TENNESSEE.

AUTOMATIC STOP FOR PHONOGRAHS.

1,401,658.

Specification of Letters Patent. Patented Dec. 27, 1921.

Application filed October 21, 1920. Serial No. 418,345.

To all whom it may concern:

Be it known that I, JOHN Z. Tow, a citizen of the United States, residing at Springfield, in the county of Robertson and State 5 of Tennessee, have invented certain new and useful Improvements in Automatic Stops for Phonographs, of which the following is a specification.

This invention relates to automatic stop 10 mechanism for sound reproduction apparatus and the general object of the invention is to provide a novel combination and arrangement of parts which will operate automatically to arrest the motion of the record supporting turn table when the stylus of 15 the reproducer has reached the inner end of the record groove.

Another object of the invention is to provide mechanism for the purpose stated so 20 constructed and operated in such a manner that the record supporting turn table will be arrested in its movement shortly subsequent to the time when the stylus of the reproducer reaches the inner end of the record 25 groove, regardless of the distance between this end of the groove and the center or axis of the record so that without any 30 necessity for adjustment, the mechanism will operate automatically in the use of records of all sizes and having different lengths of 35 grooves.

A further object of the invention is to so 40 construct the mechanism that the use thereof will involve no manual adjustments or 45 operations other than the manipulation of the starting lever as is required in all of the ordinary types of phonographs and similar machines.

In the accompanying drawings: 40 Figure 1 is a view in top plan illustrating a phonograph equipped with the improvements of the present invention, parts being broken away;

Fig. 2 is a plan view illustrating the 45 automatic stop mechanism of the invention, the parts being in the positions assumed while the machine is in operation and a record is being reproduced;

Fig. 3 is a similar view illustrating the 50 positions assumed by the parts immediately subsequent to the time the stylus of the reproducer reaches the inner end of the record groove;

Fig. 4 is a perspective view of the mechanism viewed from the under side; 55

Fig. 5 is a detail vertical sectional view through the inner end of the tone arm and the bearing therefor and illustrating the manner of mounting the member which is carried by the tone arm and which coacts 60 with the automatic stop mechanism;

Fig. 6 is a group perspective view illustrating the parts comprising the device shown in Fig. 5 disassembled;

Fig. 7 is a horizontal sectional view on the 65 line 7—7 of Fig. 5.

As the present invention resides solely in the automatic stop mechanism which operates to arrest the movement of the record supporting turn table when the stylus of the 70 reproducer reaches the inner end of the record groove, and is not concerned with the construction of any other portion of the sound reproducing apparatus, only so much of this apparatus has been illustrated in the 75 drawings as is necessary to set up an operative structure and the combination of parts covered by the appended claims. Thus the motor and its various adjuncts have been omitted from the showing as well as the 80 specific details of the several controls. Also it will be understood that while the drawings illustrate, and the description which is to follow will specifically set forth, the manner in which the mechanism of the invention 85 is adapted to one particular type of sound reproduction apparatus, the required changes may be made in this arrangement in adapting the mechanism to sound reproduction apparatus of any other standard or 90 specially designed type.

In the drawings the numeral 1 indicates in general the base board of a phonograph of the well-known type, the numeral 2 the usual spindle upon which is mounted the 95 record supporting turn table 3 and which is driven by the usual motor (not shown), the numeral 4 indicates the tone arm mounted in the usual manner and provided at its outer end with the usual reproducer 5 having the stylus 6 designed to travel in the groove of the usual record 7. The numeral 8 indicates, in the present illustration, a base plate which is mounted upon the base board 1 and which supports the motor and the 100 mechanism embodying the invention.

The combination includes a brake member which is indicated in general by the numeral 9 and this member is pivotally mounted, as at 10, upon the under side of 5 the plate 8 and includes an arm 11 which carries a brake shoe 12 designed to coact with the usual brake disk or similar brake element 12^a of the motor, when the member 9 is swung upon its pivot to one position, 10 and thus arrest the operation of the motor, and to clear the said motor brake element when the member is swung upon its pivot to another position so as to allow the motor to run free. A spring 13 is connected at 15 one end as at 14 to the under side of the plate 8 and at its other end as at 15 to an arm 16 which is pivotally mounted as at 17 upon the under side of the brake member 9 at a point at one side of the pivot 10 for 20 the said member. This arm 16 extends from its pivoted end 17 past the pivot 10 and beyond the said pivoted end of the member 9, as clearly shown in Fig. 4 of the drawings, and performs a function to be presently set forth. The arm 16 does not have 25 free movement upon its pivot 17 but on the other hand this movement is somewhat limited or more properly speaking yieldably resisted by a leaf spring 18 which is secured 30 rigidly at one end to the member 9 and at its other end is secured rigidly to the under side of the arm 16 at a point between the pivot 17 and the free end of this arm. The spring 18 is relatively stiff so that notwithstanding 35 the fact that the spring 13 is connected to the arm 16 rather than to the member 9, the said member 9 is urged by this latter spring to move about its pivot 10 so as to bring the brake shoe 12 into braking engagement with the brake element of 40 the motor. In other words the spring 13 constitutes means urging the brake member to active position and the member will assume this position unless restrained in a 45 manner and by a means to be presently described. In order that the brake member may be moved to inactive position in initially setting the mechanism in operation, a starting lever 19 is pivotally mounted as at 50 20 upon the under side of the plate 8 and at its inner end has operative connection as at 21 with the free end of the brake member 9, the said lever 19 at its outer end projecting to the edge of the plate 8 and being 55 provided with a finger piece 22 by which it may be readily manipulated.

After the brake member 9 has been initially swung upon its pivot to inactive position so as to permit the motor to run free, 60 it is held in this position by a restraining member indicated in general by the numeral 23. This member 23 comprises an arm 24 pivotally mounted as at 25 upon the under side of the plate 8 and provided with 65 a depending pin 26 which, when the mem-

ber is in active relation to the brake member 8, engages against one lateral edge of the arm 16 near the free end of the latter, as clearly shown in Figs. 2 and 4 of the drawings. A spring 28 is connected at one 70 end to the plate 8 and at its other end to the arm 24 and constitutes a means urging the arm, or in other words the restraining member 23, to assume an inactive position. In such position of the restraining member, 75 the pin 26 carried by the arm 24 will clear the edge of the arm 16 and will freely enter a notch or cutaway portion 29 formed in the free end of this arm. Thus when the parts are in the positions shown in Figs. 80 2 and 4 of the drawings and the pin 26 is in engagement against the arm 16, the brake member 9 having been previously moved to inactive position, the said brake member will be restrained from movement to active position under the influence of the spring 13, by reason of such engagement of the pin 26 against the arm 16 but it will be evident that if the arm 24 comprising the restraining member 23 is permitted to swing upon 85 its pivot under the influence of the spring 28, the pin 26 will ride out of engagement with the edge of the arm 16 and past the end of this arm or in other words enter the notch 29 so that the brake member 9, being 90 no longer restrained, will be moved through the medium of its spring 13 to bring its brake shoe 12 into engagement with the brake element of the motor. Of course during 95 the period of reproduction of the record, and while the stylus of the reproducer is still traveling in the record groove, the restraining member must be held in active position, and this is accomplished through the medium of a detent which is indicated 100 in general by the numeral 30. This detent 30 is pivoted as at 31 at one end to the under side of the plate 8 and is provided at its free end with a depending lug 32 which is designed to engage either against that 105 edge of the arm 24 which is presented in the direction in which this arm is swung under the influence of the spring 28 or seat in a notch 33 formed in this edge of the said arm. A leaf spring 34 is fixed upon 110 the under side of the plate 8 and bears against the detent 30 in a manner urging this detent upon its pivot to position such that its lug 32 will engage against the said edge of the arm 24 rather than in the notch 115 33, and when in the operation of the mechanism the detent 30 is swung upon its pivot to a position to bring its lug 32 into engagement with the notch 33, such movement is against the tension of the spring 34, and 120 subsequent release will permit it to be returned, under the influence of said spring 34, to such position that its lug will engage against the edge of the lug 24 rather than 125 in the said notch 33. Movement of the de- 130

tent in this latter direction is limited by a stop pin 35 upon the under side of the plate 8. When the detent 30 is in such position that its lug 32 will engage the edge of the 5 arm 24 at one side of the notch 33, the arm will be held, against the tension of the spring 28, in such position that this pin 26 will engage against the edge of the arm 16 of the brake member and thus restrain this 10 member from movement to active position. However, when the detent member 30 is moved upon its pivot to such position that the lug 32 will enter the notch 33, the arm 24 will be permitted to swing about its pivot 15 under the influence of the spring 28 so as to cause the pin 26 to ride out of engagement with the edge of the arm 16 and freely enter the notch 29 thus permitting the brake member 9 to be swung under the influence 20 of this spring 13 to active position.

In order that the restraining member 23 may be moved to inactive position and that the detent 30 may be automatically tripped to release the restraining member 23 at the 25 time the stylus of the reproducer reaches the inner end of the record groove, there is provided a means which will now be described. This means comprises a trip member which is indicated in general by the numeral 36 30 and which comprises an arm 37 pivotally mounted at one end as at 38 upon the plate 8 and limited in one direction of its swinging movement by engagement with a stop lug 39 upon the said plate. This arm is 35 provided at its outer end with an arcuate rack 40 and beyond the rack with a trip finger 41 having a cam edge 42 and a terminal trip lug 43. The cam edge 42 of the finger 41 is designed to ride against a pin 44 which depends from the free end of the 40 arm 24 comprising the restraining member, when the arm 37 is swung upon its pivot in the direction of the said restraining member, and the parts are so proportioned and 45 arranged that when the arm 27 is swung in the direction stated, the cam edge 42 of the finger 41 riding against the pin 44 will serve to swing the cam 24 upon its pivot to inactive position. In this movement of the arm 50 37 the trip lug 43 recedes from the lug 32 but when the arm 38 is swung upon its pivot in the opposite direction, under conditions to be presently explained, the cam edge 42 will gradually ride away from the pin 44 55 thus permitting the cam 24 to be swung upon its pivot 25 under the influence of the spring 28 until the pin 26 has substantially reached the end of the engaged edge of the arm 16 of the brake member. Then upon 60 further movement of the arm 37 in the same direction, the trip lug 43 will be brought into engagement with the lug 32 and the detent 30 will be swung upon its pivot to seat the said lug 32 in the notch 33. This 65 of course permits of further swinging move-

ment of the arm 24 under the influence of its spring 28 and results in the disengagement of the pin 26 from the arm 16 and allows the brake member to move to active position under the influence of its spring 13. 70

In order to provide for movement of the arm 37 upon its pivot in the direction of the restraining member 23 and thus effect movement of the restraining member to active position, a lever 45 is swiveled as at 46 75 upon the under side of the plate 8 and has a terminal arm 47 projecting into the path of movement of the control lever 19 when the said lever is swung to starting position. Thus when the lever 19 is swung to this position this engagement against the arm 47 of the lever 45 will result in this latter lever being swung upon its pivot, and as the other end of this lever 45, indicated by the numeral 48, moves in the path of the arm 37, 80 it will engage against this arm and swing the same in the direction stated.

It will now be evident that when the control lever 19 is swung to starting position, the trip arm 36 will, through the medium 90 of the lever 45, be swung to inactive position, effecting movement of the restraining member 23 to active position but restraining the brake member 9 in inactive position, this last mentioned member having been 95 moved to such position through the initial movement of the control lever 19.

A pinion 49 is fixed for rotation with the turn table spindle 2 and meshes with a gear 50 carrying a pinion 51 in turn meshing 100 with a gear 52. A crank pin 53 is associated with the gear 52 and is carried, in the rotation of this gear 52, in a path to intermittently bring it into mesh with the arcuate rack 40 of the trip member 36. Thus 105 if there were no counteracting force, the rotation of the turn table spindle 2 and the intermittent meshing of the crank pin 53 with the arcuate rack 40 through the operation of the train of gearing above described, would result in the rack together with the trip member 36 by which it is carried and of which it forms a part, being swung or moved in a direction away from the restraining member 23 until finally the 110 parts would be tripped and the brake would be applied. However it is necessary that this operation of the parts be postponed until the stylus of the reproducer has reached the inner end of the record groove, 115 and therefore means is provided continuously urging the trip member 36 for movement upon its pivot in the opposite direction so long as the tone arm 4 continues to be carried inwardly through the travel of 120 the stylus in the record groove. This means comprises a finger 54 which is frictionally connected with the tone arm in a manner to be presently explained and which bears 125 at its free end against a lug 55 upon the 130

arm 37, the arrangement of the parts being such that as the tone arm is carried to the left in the usual manner over the surface of the record as the stylus is traveling in 5 the record groove, the said finger 54 will bear against the lug 55 to urge the arm 37 in a corresponding direction or in other words in the direction of the restraining member 23. Thus after each successive engagement 10 of the crank pin 53 with the segmental rack 40, the arm 37 will have been moved in the opposite direction a short distance, but before the pin again meshes with the rack, the arm 37 will have been returned 15 to its original position through the moving influence of the finger 54. However when the tone arm ceases to move or swing inwardly because of the fact that the stylus of the reproducer has reached the inner end 20 of the record groove, the finger 54 will no longer exert its influence against the trip member 36, and as a consequence the intermittent meshing of the pin 53 with the rack 40 will effect swinging movement of the trip 25 member to active position in the course of which movement the parts comprising the restraining member 23 and detent 30, will be actuated as hereinbefore described so as to eventually release the brake member 9 30 and permit the same to be moved to active position under the influence of its spring 13.

It is preferable that a leaf spring 56 be arranged to bear against the pivot for the arm 36 so as to steady this arm and prevent 35 its swinging to one side or the other in the event the graphophone is not disposed in a level position.

Referring again to the spring 18, it will be understood that this spring permits of 40 the brake being applied through action of the control lever 19 when the parts are in the positions shown in Fig. 2 of the drawings and in this manner the rotation of the record supporting turn table may be stopped 45 whenever desired without the necessity of waiting until the stylus of the sound box has reached the inner end of the record groove.

As heretofore stated, the finger 54 is frictionally held for turning movement with 50 the tone arm, and the manner of mounting this finger and of varying the degree of frictional resistance offered thereby will now be described. The inner end or downward 55 bend of the tone arm is indicated by the numeral 57 and the same is rotatably mounted in the usual bearing socket 58 which is fixed upon the top board of the phonograph, being held assembled with the 60 socket by means of a pin or screw 59 fitted through the wall of the socket 58 and projecting at its inner end into the slot 60 formed in the said bend 57. The bearing 58 is interiorly increased in diameter at its 65 lower end to form an interiorly enlarged

neck 61, and disposed within this neck and bearing frictionally against the upper end wall or shoulder thereof is a friction washer 62. The arm 54 is provided at its inner end with a collar 63 which fits the lower end 70 of the bend 57 of the tone arm as does also the said washer 62, and a second washer 64 is also fitted onto the said end of the tone arm and bears against the under side of the collar 63, the upper side of the said collar 75 bearing against the washer 62. The washers 62 and 64 are formed respectively with notches 65 and 66 for the reception of a key 67 carried by and extending longitudinally of the bend 57 of the tone arm, so that these 80 washers are connected with the arm for rotation therewith. The inner periphery of the collar 63 is recessed, as at 68, for a portion of its circumference and this recess 85 likewise receives the key 67, but as the recess is of a length considerably greater than the width of the notches 65 and 66, the collar 63 is not held for rotation with the tone arm by positive coaction of the key 67 with the said collar, but on the other hand the 90 collar and the arm 54 may have pivotal movement about the bend of the tone arm, this movement being, however, yieldably resisted by the frictional contact of the washers 62 and 64 with the said collar. In 95 order that the washers and the collar may be maintained in frictional contact and that the degree of frictional resistance offered to the rotation of the collar may be varied, a collar 69 is fitted onto the lower end of the 100 bend 57 of the tone arm and within the neck 61 and bears at its upper end against the under side of the washer 64, this collar being split as at 70 to receive the key 67, and the engagement of the key in the split 105 70 serving to connect the collar 69 with the tone arm for turning movement therewith. A cross pin 71 extends diametrically of the collar 69 and connected at its lower end to this pin is a spring 72 which at its upper end is 110 connected to the lower end of a stem 73 which extends upwardly within the bend 57 of the tone arm and through an opening 74 in the upper side of the said bend. The 115 stem 73 is of rectangular or other polygonal form in cross section, and the opening 74 is similarly formed so that the stem will be held against rotation within the opening and yet may be vertically adjusted therethrough. The stem is threaded as indicated by the numeral 75 and fitted thereon is an adjusting nut 76 which bears against the upper side of the bend 57 of the tone arm, as clearly shown in Fig. 5 of the drawings, and which may be rotated so as to feed 120 the stem upwardly or downwardly and thus vary the tension of the spring 72. It will be evident that by varying the tension of this spring, the degree of force exerted by the 125 collar 69 against the washer 64 and trans- 130

mitted to the collar 63 and washer 62 to frictionally bind together these parts, may be varied.

Having thus described the invention, what is claimed as new is:

1. In automatic stop mechanism for sound reproduction apparatus, in combination with a tone arm and an element for rotating a record turn table, a trip member, means actuated through swinging movement of the tone arm for urging the said trip member in one direction, means actuated through the rotation of the turn table element for moving the trip member in another direction, a 10 brake member, means urging the same to active position, a restraining member for coaction with the brake member to hold the said brake member in inactive position, means tending to render the restraining member inactive, 70 means operable to move the brake member to inoperative position, means associated with the trip member for moving the restraining member to active position when the trip member is moved in the first mentioned direction, a detent for holding the restraining member in active position, and means actuated through movement of the trip member in the other direction for rendering the detent inactive. 80
2. In automatic stop mechanism for sound reproduction apparatus, in combination with a tone arm and an element for rotating a record turn table, an oscillatory trip arm, means coacting with the arm and actuated through swinging movement of the tone arm for urging the said trip arm in one direction, means actuated through rotation of the turn table element and intermittently coacting with the trip arm to move the same in another direction, a brake member, means urging the same to active position, means operable to move the brake member to inactive position, means for holding the brake member in inactive position, and means actuated through movement of the trip arm in the last mentioned direction for rendering the holding means inactive. 90
3. In automatic stop mechanism for sound reproduction apparatus, in combination with a tone arm and an element for rotating the record turn table, a trip member, means actuated through swinging movement of the tone arm for urging the said trip member in one direction, means actuated through rotation of the turn table element and intermittently coacting with the trip member for moving the trip member in another direction, a 35 brake member, means urging the same to active position, a restraining member for coaction with the brake member to hold said brake member in inactive position, means tending to render the restraining member inactive and means operable to move the brake member to inactive position, means for moving the restraining member to active position when the trip member is moved in the first mentioned direction, a detent for holding the restraining member in active position, and means actuated through movement of the trip member in the other direction for rendering the detent inactive. 105
4. In automatic stop mechanism for sound reproduction apparatus, in combination with a tone arm, an element for rotating a record turn table, a trip member, means actuated through swinging movement of the tone arm for urging the said trip member in one direction, means actuated through rotation of the turn table element for moving the trip member in another direction, a 110 brake member, means urging the same to active position, a control lever operatively connected with the brake member and operable to move the brake member to inactive position, operative means between the control lever and the trip member for moving the trip member in the first mentioned direction when the control lever is moved to position to render the brake member inactive, means for holding the brake member in inactive position, and means actuated through movement of the trip member in the other direction for rendering the holding means 115 inactive. 120
5. In automatic stop mechanism for sound reproduction apparatus, in combination with a tone arm and an element for rotating a record turn table, a trip member, means actuated through swinging movement of the tone arm for urging the said trip member in one direction, means actuated through rotation of the turn table element for moving the trip member in another direction, a 125 pivot member, means urging the same to active position, a restraining member for coaction with the pivot member to hold the said pivot member in active position, means tending to render the restraining member inactive, 130

oted brake member, means urging the same to active position and coacting therewith at one side of the pivot, means carried by the brake member and extending to the other side of the pivot, a restraining member for coaction with the last mentioned means to limit the movement thereof and thus limit the movement of the brake member and hold the same in inactive position against the influence of its moving means, means for holding the restraining member in active position, and means for coöperation with the holding means to render the same inactive upon movement of the trip member in the other direction.

7. In automatic stop mechanism for sound reproduction apparatus, in combination with a tone arm and an element for rotating a record turn table, a trip member, means actuated through swinging movement of the tone arm for urging the said trip member in one direction, means actuated through rotation of the turn table element for moving the trip member in another direction, a pivoted brake member, means urging the same to active position and operatively connected therewith at one side of its pivot, an arm pivotally mounted upon the brake member and extending to the other side of the pivot, means yieldably resisting movement of the said arm upon its pivot, a restraining member having an abutment element, means actuated through movement of the trip member in the first mentioned direction to move the restraining member to position with its abutment element engaging against the said arm upon the brake member whereby to sustain the brake member against movement to active position, a detent having a lug for engagement with the said restraining member for holding the same in active position, a restraining member having a cutaway portion in which the said lug may engage in another position of the detent, and means carried by the trip member for coaction with the lug upon the detent, upon movement of the trip member in the other direction, whereby to move the detent to position with its lug engaging in the said cutaway portion of the restraining member and thereby release the restraining member for movement to inactive position to in turn release the brake member for movement to active position.

8. In automatic stop mechanism for sound reproduction apparatus, in combination with a tone arm and an element for rotating a record turn table, a trip member, means actuated through swinging movement of the tone arm for urging the said trip member in one

direction, means actuated through rotation of the turn table element for moving the trip member in another direction, a pivoted brake member, means urging the same to active position and operatively connected therewith at one side of its pivot, an arm pivotally mounted upon the brake member and extending to the other side of the pivot, means yieldably resisting movement of the said arm upon its pivot, a restraining member having an abutment element, means actuated through movement of the trip member in the first mentioned direction to move the restraining member to position with its abutment element engaging against the said arm upon the brake member whereby to sustain the brake member against movement to active position, a detent having a lug for engagement with the said restraining member for holding the same in active position, a restraining member having a cutaway portion in which the said lug may engage in another position of the detent, and means carried by the trip member for coaction with the lug upon the detent, upon movement of the trip member in the other direction, whereby to move the detent to position with its lug engaging in the said cutaway portion of the restraining member and thereby release the restraining member for movement to inactive position to in turn release the brake member for movement to active position.

9. The combination with a phonographic tone arm and a bearing in which the inner end of the arm is mounted for rotation, of an automatic-stop-mechanism control-arm pivotally mounted upon the said end of the tone arm, means upon the said end of the tone arm fractionally coacting with the said control arm to resist movement of the latter with relation to the tone arm, a spring connected with the said means, means for varying the tension of the spring, the said means comprising a threaded stem extending upwardly through the tone arm, and an adjusting nut threaded upon the stem and bearing against the exterior of the tone arm.

In testimony whereof I affix my signature.

JOHN Z. TOW. [L.S.]
